US0D1025804S

(12) **United States Design Patent** (10) Patent No.: **US D1,025,804 S**
(45) Date of Patent: ** May 7, 2024

(54) **DOORBELL BRACKET**

(71) Applicant: **Feng Shi**, Shenzhen (CN)

(72) Inventor: **Feng Shi**, Shenzhen (CN)

(73) Assignee: **Feng Shi**, Shenzhen (CN)

(**) Term: **15 Years**

(21) Appl. No.: **29/917,845**

(22) Filed: **Nov. 22, 2023**

(51) LOC (14) Cl. **10-05**

(52) U.S. Cl.

USPC **D10/121**

CLAIM

The ornamental design for a doorbell bracket, as shown and described.

DESCRIPTION

FIG. 1 is a front perspective view of a doorbell bracket, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the doorbell bracket, which form no part of the claimed design.
